UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

1,404,184.

Specification of Letters Patent. Patented Jan. 24, 1922.

Application filed October 9, 1917. Serial No. 195,533.

To all whom it may concern:

Be it known that I, REUBEN B. BENJAMIN, a citizen of the United States, residing at Chicago, in the county of Cook and State of Illinois, have invented new and useful Improvements in Electrical Connecter Devices, of which the following is a full, clear, concise, and exact description, reference being had to the accompanying drawing, forming a part of this specification.

My invention relates to electrical connector devices.

One of the objects of my invention is to provide an improved connecter device having a binding-terminal which will be simple in construction, easy to operate, cheap to manufacture, and easy to wire. Further objects will appear from the detailed description to follow and from the appended claims.

In the drawings, in which one embodiment of my invention is shown—

Fig. 1 is a side elevation of a receptacle embodying my invention;

25 Fig. 2 is a plan view of Fig. 1;

Fig. 3 is a section on the line 3—3 of Fig. 2;

Fig. 4 is a plan view of the open end of the receptacle;

30 Fig. 5 is a section on the line 5—5 of Fig. 2;

Fig. 6 is a detail sectional view on the line 6—6 of Fig. 5;

Fig. 7 is a detail sectional view on the line 35 7—7 of Fig. 5; and

Fig. 8 is a detail perspective view of a clamping member.

Referring now to the drawings in detail, the receptacle shown comprises an insulating base 10, shell and center contacts 11 and 12, respectively, supported by said insulating base, and binding-terminals 13 and 14, respectively, for the shell and center contacts, also supported by said insulating base.

45 The base 10 may be provided with ears or flanges 15 through which screws 16 may be inserted, whereby the base may be secured to any suitable support 17.

50 The shell contact 11 is located in a cup-shaped portion of the base 10 and is secured to the base by means of a pair of screws 18 extending through a flange portion 19 of the shell and threaded into nuts 20.

The center contact 12 may be secured to 55 the base 10 by means of an eyelet 21.

The binding-terminal 13 for the shell contact comprises a pair of screws 22 extending through openings in the flange 19 and threaded into a clamping plate 23. The 60 binding-plate 23 is provided with a transversely-extending groove 24 to accommodate the bared end of the leading-in conductor. The heads 25 of the screws 22 are so close together that they form a substantially continuous bearing between the shanks of the screws, to resist the reaction of the leading-in conductor thereagainst when the clamping plate 23 is drawn up by means of the screws 22.

70 The insulating base 10 is provided with a lateral opening 26 through which the bared end of the leading-in conductor may be inserted between the clamping plate 23 and the flange 19. The groove 24 may be made 75 flaring at the side of the plate nearest the opening 26, as indicated at 27 (Fig. 8) to facilitate the entry of the end of the leading-in wire.

75 The binding-terminal 14 for the center contact is constructed in substantially the same manner as the binding-terminal for the shell contact just described. A conductor-plate 28 is secured in place underneath the base of the center contact 12 by means of the 80 eyelet 21, the plate 28 leading from the binding-terminal 14 to the center contact 12. Through this plate 28 a pair of screws 29 are inserted, threaded into a binding-plate 30 similar in all respects to the clamping 85 plate 23 previously described.

90 The insulating base 10 is provided with a lateral opening 31, through which the end of the leading-in conductor may be inserted between the binding or clamping plate 30 95 and the conductor plate 28.

95 In wiring the device, the bared end of the leading-in conductor for the shell contact is inserted between the clamping-plate 23 and the flange 19, and the screws 22 are 100 tightened up to draw the clamping-plate 23 toward the heads 25 of the screws and to clamp the end of the leading-in conductor between the clamping-plate 23 and the flange 19. The heads 25 of the screws "back up" 105 the relatively-thin material of the flange 19 and prevent the latter from being distorted when the screws 22 are tightened up. In a

- similar manner, the leading-in conductor for the center contact is inserted between the clamping-plate 30 and the conducting-plate 28, and the screws 29 are drawn up to clamp 5 the end of the leading-in conductor firmly in place. In this terminal, also, the heads of the screws "back up" the relatively-thin conductor-plate 28 and prevent its distortion.
- 10 I claim as new and desire to secure by Letters Patent of the United States—
1. A receptacle comprising a body of insulating material, center and side contacts carried by said body, said side contact having an inwardly extending flange, said insulating body having an outwardly opening recess underneath said flange, a clamping plate located in said recess, and a pair of screws extending through said flange portion and threaded into said clamping plate.
  2. A binding-terminal comprising two screws having their shanks substantially parallel and their heads so close together that they form a substantially continuous bearing between said shanks for the reaction of the leading-in conductor thereagainst, and a relatively-thin sheet-metal member through which the shanks of said screws extend, located between the leading-in conductor and screw-heads, whereby said thin sheet-metal is supported by said screw-heads, and a metal clamping member into which said shanks are threaded, whereby said clamping member may be drawn toward said sheet-metal member by the action of said screws.
  3. A receptacle comprising a body of insulating material, center and side contacts carried by said body, a member of conducting material electrically connected with said center contact, said insulating body having an outwardly opening recess underneath said conducting member, a clamping plate located in said recess, and a pair of screws extending through said conducting member and threaded into said clamping plate.
  4. An electrical connector device comprising an insulating base, shell and center contacts supported thereby, and a binding-terminal for one of said contacts comprising a screw the axis of which is substantially parallel to the axis of the shell and the head of which is accessible through the shell contact, and a movable clamping member into which said screw is threaded, whereby it may be drawn toward the head of said screw, said base having a lateral opening through which a leading-in conductor may be inserted between said clamping member and the head 60 of said screw.

5. An electrical connector device comprising an insulating base, shell and center contacts supported thereby, and a binding-terminal for one of said contacts comprising two screws the axes of which are substantially parallel to the axis of the shell and the head of which is accessible through the shell contact, the heads of said screws being so close together that they form a substantially continuous bearing between the shanks of 70 said screws for the reaction of the leading-in conductor thereagainst, a relatively-thin sheet-metal conductor member through which the shanks of said screws extend, located between the leading-in conductor and 75 the screw-heads, whereby said thin sheet-metal conductor member is supported by said screw-heads, and a movable clamping member into which said screws are threaded whereby it may be drawn toward said thin 80 sheet-metal member, said base having a lateral opening through which the leading-in conductor may be inserted between said clamping member and said conducting member.

6. An electrical connector device comprising an insulating base, shell and center contacts supported thereby, and a binding-terminal for one of said contacts comprising two screws the axes of which are substantially parallel to the axis of the shell, the heads of said screws being so close together that they form a substantially continuous bearing between the shanks of 85 said screws for the reaction of the leading-in conductor 90 thereagainst, said shell contact having an inwardly-extending flange through which said screws extend, located between the leading-in conductor and screw-heads, whereby said flange is supported by said screw-heads, and a movable clamping member into which said screws are threaded, whereby said member may be drawn toward said flange, said base having a lateral opening through which the leading-in conductor may be inserted between 95 said clamping member and said flange.

7. A receptacle comprising a body of insulating material, center and side contacts carried by said body, one of said contacts being provided with a conducting member 100 electrically connected therewith, said insulating body having an outwardly opening recess underneath said conducting member, a clamping plate located in said recess and a pair of screws extending through said 105 conducting member and threaded into said clamping plate.

In witness whereof, I have hereunto subscribed my name.

REUBEN B. BENJAMIN.
